(57) **CLAIM**

The ornamental design for a telescoping anode pole, as shown and described.

DESCRIPTION

FIG. 1 is a side elevation view of the telescoping anode pole, with the break line indicating indeterminate length;

FIG. 2 is an end view of the telescoping anode pole.

FIG. 3 is a side perspective view of the telescoping anode pole;

FIG. 4 is an opposite side perspective view of the telescoping anode pole; and,

FIG. 5 is an enlarged view of the handle portion of the telescoping anode pole.
